ENERGY REFLECTOR

Frederick R. Ruble, Stow, Ohio, assignor to Goodyear
Aerospace Corporation, Akron, Ohio

Filed Nov. 21, 1969, Ser. No. 20,227

Term of patent 14 years

Int. Cl. D14—03

U.S. Cl. D26—14

FIG.-2

FIG.-3

FIG.-4

FIG. 1 is a perspective view;

FIG. 2 is an elevational view;

FIG. 3 is a bottom plan view; and

FIG. 4 is an elevational view taken ninety degrees with respect to FIG. 2.

The design for an energy reflector is characterized by ribs supporting a surface having orthogonal concave and convex curvatures.

I claim:

The ornamental design for an energy reflector, as shown and described.
